UNITED STATES PATENT OFFICE.

WILLIAM D. GHARKY, OF PHILADELPHIA, PENNSYLVANIA.

DESIGN FOR A TELEPHONE-INSTRUMENT CASE.

SPECIFICATION forming part of Design No. 32,615, dated May 1, 1900.

Application filed April 2, 1900. Serial No. 11,270. Term of patent 7 years.

To all whom it may concern:

Be it known that I, WILLIAM D. GHARKY, a citizen of the United States, residing at Philadelphia, in the county of Philadelphia and State of Pennsylvania, have invented and produced a new and original Design for Telephone-Instrument Cases, of which the following is a specification, reference being had to the accompanying drawings, forming part thereof.

Figure 1 is a front view of a telephone-instrument case, showing my new design. Fig. 2 is a side view of the same, showing the lower part in section, taken on the line xx of Fig. 1.

As shown in the drawings, the leading or material feature of my design consists of the body portion A, expanding to form the projecting flange B. In the interior and centrally located with reference to the front and rear

of the case is another flange C, which projects 20 inwardly. The position of this flange is clearly indicated in Fig. 2, where part of the side of the case is cut away, giving a view of the interior. This flange and its location within the case are the most material features 25 of my design.

Having described my invention, what I claim as new, and desire to secure by Letters Patent, is—

The design for a telephone-instrument case, 30 as herein shown and described.

In testimony whereof I have signed my name to this specification in the presence of two subscribing witnesses.

WM. D. GHARKY.
